George Reed

United States Patent Office.

ALBION S. SKILLIN AND GEORGE W. REED, OF PORTLAND, MAINE, ASSIGNEES TO THEMSELVES, HENRY L. HANSON, AND J. L. BUTLER, OF THE SAME PLACE.

Letters Patent No. 68,463, dated September 3, 1867.

IMPROVED NUTMEG-GRATER.

The Schedule referred to in these Letters Patent and making part of the same.

TO ALL WHOM IT MAY CONCERN:

Be it known that we, ALBION S. SKILLIN and GEORGE W. REED, of Portland, in the county of Cumberland, and State of Maine, have invented a new and useful improved Rotary Nutmeg-Grater; and we hereby declare the following to be a full, clear, and exact description thereof, which will enable others to make and use our invention, reference being had to the accompanying drawings, forming part of this specification, in which—

Figure 1 shows a top plan of our invention.

Figure 2 is an edge view of the same.

The object of our invention is the production of a cheap and convenient device for grating nutmegs.

Our invention consists, first, of a stock or handle, having a pocket and thimble; second, of a rotary grater, operated by a crank or handle; third, of a spring-arm, having a head which fits into the thimble.

In the accompanying drawings, *a* shows the stock, *b* shows the rotary grater, *c* shows the spring-arm, *d* the thimble, *e* the head on the spring-arm, *f* the crank or handle of the rotary grater. The head *e* on the spring-arm *c* can be lifted out of the thimble *d*, and the arm swung to one side, as indicated by dotted lines in fig. 1. The pocket or hole through the head of the stock *a* is shown by dotted lines 1 in fig. 2. The arm *c* may be pressed down, so that the head *e* thereof will fill the pocket in the stock *a*. This is indicated by dotted lines 2 in fig. 2. The rotary grater revolves upon the pivot *h*.

The operation of the device is as follows: Lift the head *e* out of the thimble *d*, and swing the arm *c* to one side, as shown in fig. 1 by dotted lines. Place the nutmeg in the thimble *d*, and return the arm and its head *e* back into the thimble. The nutmeg will then be pressed against the roughened and perforated surface, 3, fig. 1, of the rotary grater. The handle *a* is then grasped by one hand, which, at the same time, embraces the arm *c* and maintains a continuous pressure of the head *e* upon the nutmeg. Revolve the grater *b* by its handle *f*, and the particles of the nutmeg, falling through the perforations in the grater, are deposited wherever desired. It is evident that the nutmeg can be preserved in the thimble *d* when the device is not in use, being there retained by the arm *c*. The arm *c* can be turned aside on the pivot *m*.

It will be perceived that the grater *b* is composed of two parts, viz, the perforated face 4, and the flange 5, upon which the said face 4 is attached. This flange is made flaring on its inner side to allow the free escape of the ground particles of the nutmeg, and it may be made by casting or in any convenient method.

We do not claim broadly a rotary nutmeg-grater, for this is not new, neither do we claim any arrangement of the parts constituting such a grater except the one herein shown and described. We also desire to disclaim a rotary grater composed of a metallic corrugated disk, which is the base of the cylinder, and having a lever and follower to regulate the feed of the machine, as exhibited in the application of Edmund Brown and Albert Hadley, withdrawn November 18, 1854. Our invention consists of a rotary perforated grater, through which the ground particles fall upon the article upon which they are desired to be deposited, in combination with a handle, upon which is affixed the spring-arm *c*, having a head, *e*, the arm *c* being capable of being lifted out of the thimble *d* and turned to one side, as shown in fig. 1.

What we claim as our invention, and desire to secure by Letters Patent, is—

The arrangement of the handle or stock *a*, the rotary grater *b*, spring-arm *c*, thimble *d*, and head *e* for a rotary nutmeg-grater, as herein set forth and described.

ALBION S. SKILLIN,
GEORGE W. REED.
